UNITED STATES PATENT OFFICE.

GEORGE L. THOMPSON, OF CHICAGO, ILLINOIS.

DESIGN FOR A BICYCLE-FRAME.

SPECIFICATION forming part of Design No. 30,499, dated April 4, 1899.

Application filed January 13, 1899. Serial No. 702,108. Term of patent 7 years.

To all whom it may concern:

Be it known that I, GEORGE L. THOMPSON, of Chicago, county of Cook, and State of Illinois, have invented and produced a new and original Design for a Bicycle-Frame, of which the following is a specification.

My novel design relates to that form of safety-bicycle frame known as the "three-crown frame;" and its characteristic and essential features consist of the triangular formation of the "stays" and "rear forks" of the rear frames between the fork-crowns and the axle-stubs, as shown in the accompanying drawings.

Figure 1 is a perspective view of a bicycle-frame embodying my novel design. Fig. 2 is a sectional detail taken on line 2 2 of Fig. 1.

In the drawings, A designates the frame as a whole; A', its rear stays, which extend downwardly and rearwardly from the crown a, that is attached to the seat-post cluster a', and A² the rear forks, which extend rearwardly to

meet the stays A' from the crown a², that is attached to the rear of the crank-hanger a³. Both the stays and forks are made triangular in cross-section, as shown in Fig. 2, the apex of the triangle being directed outwardly and the triangular formation extending from their juncture with the crowns a and a² almost to their juncture with each other at a⁴. Aside from this feature the frame is of the usual appearance and need not be more particularly described.

I claim as my new and original design—

The design for a bicycle-frame substantially as herein shown and described.

In testimony that I claim the foregoing as my invention I affix my signature hereto, in the presence of two subscribing witnesses, this 21st day of December, A. D. 1898.

GEORGE L. THOMPSON.
